Primary Examiner — Jack Reickel*Assistant Examiner* — Michael A Kervin(74) *Attorney, Agent, or Firm* — Davis & Kuelthau, sc;
Joseph S. Heino; Erin E. Kaprelain(57) **CLAIM**

The ornamental design for a baseball bed leg cover, as shown and described.

DESCRIPTION

FIG. 1 is a front perspective view of a baseball bed leg cover showing my new design;

FIG. 2 is a rear perspective view thereof;

FIG. 3 is a top plan view thereof;

FIG. 4 is a bottom plan view thereof;

FIG. 5 is a rear elevation view thereof; and,

FIG. 6 is a front elevation view thereof.

The dot-dash broken lines define the bounds of the claimed design and form no part thereof.

1 Claim, 6 Drawing Sheets(56)
